Primary Examiner — Rosemary K Tarcza*(74) Attorney, Agent, or Firm* — J. Richard Soderberg**CLAIM**

The ornamental design for an electric-vehicle connector post, substantially as shown and described.

DESCRIPTION

FIG. 1 shows a perspective view of an embodiment of an electric-vehicle connector post.

FIG. 2 is a front view thereof.

FIG. 3 is a top view thereof.

FIG. 4 is a side view of one side thereof, the other side being a mirror image; and,

FIG. 5 is a rear view thereof.

The broken lines are for illustrative purposes and form no part of the claimed design.
